POWDER CONTAINER AND BLOWER
PACKAGE

Edward T. Ahern, New Haven, Conn.; Irene D. Ahern administratrix of the estate of said Edward T. Ahern, deceased

Application April 27, 1943, Serial No. 484,714

8 Claims. (Cl. 43—146)

This invention relates to powder container and blower packages, the same being an improvement upon my earlier invention disclosed by Patent Number 2,302,591, issued November 17, 1942.

With reference to the accompanying drawing, Figure 1 is a longitudinal sectional view on the line 1—1 of Figure 2; Figure 2 is a top plan view of the package; Figure 3 is a fragmentary longitudinal sectional view of the package with the tube extended therefrom ready for use; Figure 4 is another longitudinal sectional view on the line 4—4 of Figure 1; Figure 5 is a cross-sectional view on the line 5—5 of the Figure 1; Figure 6 is a detail cross-sectional view in perspective of the bottom of package; Figure 7 is an enlarged perspective sectional view of flanged enclosing members; Figure 8 is a detail cross-sectional view on the line 8—8 of Figure 1; Figure 9 is a top plan view of a modified package; and Figure 10 is a fragmentary longitudinal sectional view on the line 10—10 of Figure 9.

With more particular reference to the accompanying drawing, the tubular container 1 of the package is provided with the flexible side structure 1' and a permanently closed end 2. A filler element comprises the cylindrical wooden block 3 and the flanged paper discs 5 and 7. The block 3 has a central bore 4 therethrough and is fixedly enclosed by the discs 5 and 7, the upper disc 5 having the flange 5' and the central perforation 6, and the lower disc 7 having the flange 7' and the central perforation 8. The discs 5 and 7 are each sealed to the top and bottom surfaces of the block 3, respectively, and the flanges 5' and 7' are each sealed to the inner surface of the tubular side structure 1' adjacent the upper end 2' of the package. The disc 5 is the floor of a chamber 9 which has no communication with the powder portion of the container 1 excepting through said perforation 6, bore 4, and perforation 8. An adhesive element G is employed to seal the filler element parts.

The cap 15 for the tubular container package may be made movable or immovable or movable in part. The cap 15 consists of an annular flat top having the spaceous annular opening 15' and the annular flange 17 extending at right angles therefrom. The opening 15' is provided thereunder with the transparent sheet insert 16 of cellulose acetate, the cap thus described being placed upon the end 2' of the package to enclose the chamber 9.

The tube 12 at its lower end is provided with the tubular enlargement 13 and the opposite free end 14 is slidingly inserted through the perfora-

tion 8 of the lower paper disc 7, bore 4 of the block 3 and the perforation 6 of the upper paper disc 5 before the filler element is secured and sealed to the side structure 1'. The perforations 6 and 8 of the paper discs 5 and 7 of the filler element are intended to be capable of frictionally holding the tube 12 in any longitudinal adjustment therein, while the bore 4 in the block 3 is made sufficiently large to allow for atmospheric changes of the wooden block 3. The tube 12 within the container 1 is preferably of such length that its enlarged end 13 contacts with, and rests upon, the bottom 2 of the container 1, but may be less long if desired. Whatever the length of the tube 12 may be, it is maintained, for the purposes of shipment, as illustrated by the Figures 1 and 2, within the container 1, frictionally held by the perforations 6 and 8, so that the tube end 14 is firmly presented against the under surface of the sheet insert 16 of the cap 15, such contact of the tube end 14 and the insert 16 constituting a closure for the tube 12 and hence for the powder container portion of the package.

Depending, by means of the fasteners 11, from the filler element are the two arms of the spring means 10, each contacting under tension diametrically opposite one another with the inner surface of the flexible tubular side structure 1', approximately along the dotted lines 5—5 of the Figure 1.

The package is not intended to be refilled. The powder is placed within the container 1 before it is sealed up by means of the filler element. The initial powder content is limited to about two-thirds of the container's cubic capacity. The package fully assembled as aforesaid and with its powder content is ready for shipment, as illustrated by the Figure 1.

In the hands of the user, the cap 15, with its insert 16, is eliminated in whole or in part. The tube 12 which before the elimination of the cap 15 may be seen through the transparent insert 16, can now be manually pulled out to its extended position limited by the engagement of the enlargement 13 with the annular wall of the perforation 8 of the lower disc 7 of the filler element, as illustrated by the Figure 3.

With the free end 14 of the tube 12 directed upon the object to be dusted, the container 1 may be alternately contracted, and expanded from its contracted condition, by means of intermittent squeezing operation of the flexible side structure 1' by the pressure of a thumb and finger at approximately along the dotted line

5—5 of the Figure 1, thereby blowing portions of the powder content into the tubular enlargement 13 and out at the free end 14 of the tube 12. The arms of the spring 10 are intended to facilitate the return of the side structure 1' to normal position, but even without the employment of the springs 10, the flexibility of the side structure 1' has proven sufficient to restore such normal condition after each contraction of the side structure 1'.

It is advisable that, whenever it is desired to return the extended tube 12 to its position within the container 1, the package be held upside-down so that the powder content may be shifted within the container 1 in the direction of the filler end, thereby permitting the enlarged end 13 of the tube 12 to engage the bottom 2 free from powder.

Figures 9 and 10 illustrate a slight modification of the form illustrated by the Figures 1 to 8, inclusive, of the package. This modification utilizes the same container 1 and flexible side structure 1' as the preferred form, but dispenses with the chamber 9 and introduces in place thereof the chamber 9' provided by and within the annular wooden block 3' having the bore 4' therethrough, the bore 4' being counterbored to provide the chamber 9'. The wooden block 3' is formed out of kiln-dried wood treated with drying oil to avoid subsequent atmospheric changes in dimensions and therefore is fitted snugly to and held within the side structure 1' flush with the top rim 2' of the container 1. A disc 5'', having the central perforation 6' is fitted within and secured to the base of the chamber 9' by means of an adhesive element. A disc 7'' having the central perforation 8' is similarly secured to the under surface of the wooden block 3', the wooden block 3' and the discs 5'' and 7'' constituting a filler element.

The tube 12', as in the instance of the tube 12 of the Figures 1 and 2, may be of any length limited only by the container 1. The tube 12', illustrated by the Figure 10, intentionally omits the enlarged end, present as at 13 in the Figures 1, 3 and 4, but if desired, the modification may include such enlargement. In assembling without such enlargement, either end of the tube 12' may be inserted from the exterior within the chamber 9' and into the perforation 6' of the disc 5'', bore 4' in the wooden block 3' and perforation 8' of the disc 7'' before the cap 15'' is placed over the container top, the tube 12' being adjustably held within the container 1' by means of the perforations 6' and 8' during shipment or extended for use. In assembling the modification involving a tube 12' with an enlarged end, as at 13 in Figures 1, 3 and 4, of course the free end 14' would have to be inserted through the filler element from its bottom side as explained and illustrated with regard to the Figures 1, 3 and 4.

In the form illustrated by the Figure 10, as well as the Figures 1, 3 and 4, the flanged cap 15'' or 15 may be removable or permanently secured to the container 1 by means of an adhesive element. In the modified form, the cap 15'' is provided with an opening 15''' of a diameter equal at least to that of the chamber 9'. A transparent insert 16' is secured to the cap 15''' in any desired manner beneath the opening 15''', and the tube 12' is so longitudinally adjusted within the filler element as to be firmly presented to the under surface of the insert 16', such contact, as in the instance of the form illustrated

by the Figures 1, 3 and 4, constituting a closure of the tube 12', and hence of the powder containing portion of the container 1.

In the hands of the user of the modified form 5 of package, the cap 15'' is eliminated in whole or in part to manually reach and extend the tube 12' which first may be seen through the transparent insert 16', such elimination being 10 accomplished by either removing the cap 15'', if removable, or puncturing the insert 16' of an immovable cap 15''.

In either form of package, should the tube 12 or 12' become clogged with powder, an insertion 15 of a wire within such tube will readily free the tube interior for use.

While the wooden block 3' is herein described as being secured to the side structure 1', it is to be understood that such block 3' if desired may just as well be secured to the under surface of the cap 15'' where the cap 15' is made immovable. In that event, the insert 16' would then have to be secured upon the top surface of the cap 15'' over the opening 15''' and a disc (not illustrated) having a central opening would be marginally secured to the top surface of the transparent insert 16'.

I claim:

1. A powder container and blower package comprising an elongated hollow body having a flexible side wall, said body having a fixed lower capped end and a removable upper capped end; a filler within said body and having a central opening, said filler separating the interior of the body into a powder containing portion adjoining said lower end and a chamber portion adjoining said upper end, said opening connecting the powder containing portion and the chamber portion; a tube slidably positioned snugly within said opening for longitudinal adjustment 30 therein; an enlargement on the lower end of said tube; said upper capped end constituting a closure means and firmly engaging the upper end of said tube; means by which the upper capped end may be eliminated in whole or in part to make the tube accessible for manual extension; and spring means suspended from the lower end of said filler and extending within said powder containing portion, said spring means engaging opposite inner surfaces of said wall to augment the 35 flexibility of said wall, thereby insuring immediate return to normal of said wall after it has been partially collapsed.

2. A powder container and blower package comprising an elongated hollow body having a flexible side wall, said body being provided with a fixed lower end; a filler within said body and having an opening, said filler separating the interior of the body into a powder containing portion adjoining said lower end and a chamber portion at the upper end, said opening connecting the powder containing portion and the chamber portion; a tube slidably and snugly positioned within said opening for longitudinal adjustment therein; a closure for the powder containing portion consisting of a capped upper end of said body and having a transparent insert firmly engaging the upper end of said tube; and an enlargement on the lower end of said tube, said closure means being adapted to be eliminated in whole or in part to make the tube accessible for manual extension.

3. A powder container and blower package comprising an elongated hollow body with flexible side wall and a closed lower end; a filler within said body and having an opening, said

filler separating the interior of the body into a powder containing portion adjoining said lower end and a chamber adjoining the upper end of said body, said opening connecting the container portion and the chamber portion; a tube slidably and snugly positioned within said opening for longitudinal adjustment therein; and a closure for said tube, said closure consisting of a capped upper end of said body and firmly engaging the upper end of said tube.

4. A powder container and blower package comprising an elongated hollow body with an inwardly collapsible side wall and a closed lower end; a filler within said body and having an opening therethrough connected with the interior of said body adjoining said lower end; a tube slidably and snugly positioned within said opening for longitudinal adjustment therein; a closure means for said tube, said closure consisting of an upper capped end of said body and having a transparent insert firmly engaging the upper end of said tube; and means by which the upper capped end may be eliminated in part to expose the tube for manual extension.

5. A powder package comprising an elongated hollow body having a lower closed end and an upper capped end; a filler within the hollow body adjacent said upper end thereof and having an opening therethrough, the filler separating the interior of the body into a powder containing portion adjoining said lower end and a chamber portion adjoining said upper end; a tube slidably and snugly positioned within said opening for longitudinal adjustment therein; said upper capped end constituting a closure means for the container and firmly engaging the upper end of said tube; and means by which the upper capped end of said body is made removable to provide access to the said upper end of the tube for manual extension.

6. A powder blower package comprising a con-

5 tainer having an inwardly collapsible side wall, said container having a removable capped upper end and a permanently closed lower end; a filler fixedly mounted within the container adjacent said capped upper end and provided with an opening therethrough; and a tube slidably positioned within said opening for longitudinal adjustment therein, said container constituting bellows for blowing a powder content from within the container through the tube for dispensing said content at its outer end; said capped upper end constituting a detachable closure for said container and firmly engaging the upper end of said tube.

10 15 20 25 30 35 40

7. A powder blower package comprising an elongated hollow body having a capped upper end, said body including a container portion having a permanently closed lower end; a filler within said body adjacent said capped upper end and having an opening therethrough, the opening communicating with said container portion; and a tube slidably and snugly positioned within said opening for longitudinal adjustment therein; said capped upper end constituting a closure for the upper end of said tube and firmly engaging said upper end.

8. A powder blower package comprising a casing including a flexible side wall and a closed lower end; a filler within the upper end of the casing and separating therein an upper chamber portion from a powder containing portion; an opening extending through said filler and connecting the chamber portion and the powder containing portion; a tube slidably and snugly positioned within said opening and adapted to be moved therein to two extreme and intermediate positions; and a cover fitted over and closing said upper chamber and firmly engaging the upper end of said tube.

EDWARD T. AHERN.
